BELT BUCKLE

Herbert Buchsbaum, Chicago, Ill.

Application September 7, 1937, Serial No. 162,720

4 Claims. (Cl. 24—191)

The present invention relates to belt buckles and is particularly directed toward improvements in belt buckles of the character wherein a rocking gripping element is adapted to clamp the belt against a cover plate, the gripping element being carried by a member pivoted to the cover plate and having means to attach one end of the belt thereto.

The present invention contemplates improvements in devices of this character whereby the same buckle will grip a thick or a thin belt with equal facility.

The invention also contemplates improvements in the gripping mechanism whereby the structure is simplified and the cost of production thereof is materially reduced.

More particularly, the present invention contemplates an improved belt buckle having a cover plate with turned down side flanges that are extended inwardly toward each other to provide a guide for the belt and to provide hinge portions to receive a gripper carrying plate to which one end of the belt may be attached. The gripper carrying plate is provided with an end portion turned toward the cover plate to which the gripping element is attached. The gripping element has a limited rocking movement and may also slide on the gripper carrying plate toward and away from the cover plate to adapt the buckle for different thicknesses of belt.

Certain improvements are also provided in the gripping element itself whereby to improve the gripping characteristics thereof.

The features and advantages of the invention will appear more fully as the description proceeds, reference being had to the accompanying drawing wherein a preferred form of the invention is shown. It is to be understood, however, that the drawing and description are illustrative only and are not to be taken as limiting the invention except in so far as it is limited by the claims.

In the drawing—

Fig. 1 is a sectional view taken on the line 1—1 of Fig. 2 showing the buckle applied to a belt;

Fig. 2 is a bottom plan view looking up at Fig. 1;

Fig. 3 is a sectional view on the line 3—3 of Fig. 1;

Fig. 4 is a sectional view similar to Fig. 1 showing a changed position of the parts;

Fig. 5 is a sectional view taken substantially on the line 5—5 of Fig. 2;

Fig. 6 is an enlarged sectional view taken on

the line 6—6 of Fig. 3, the cover plate and belt being left off for the sake of clearance;

Fig. 7 is a perspective view showing the gripper carrying plate before the gripper element is attached; and

Fig. 8 is a plan view of the gripping element.

Referring now to the drawing, the belt buckle is made up of a cover plate 10 which is curved longitudinally and transversely to provide a slightly convex outer surface. The cover plate 10 has side portions 11 and 12 turned downwardly and then inwardly toward each other to provide a pair of spaced guide flanges 13 and 14 through which the free end of a belt 15 may be guided. The flanges 13 and 14 also are provided with tongues 16 and 17 which are bent around into loop form to provide pivots for a gripper carrying and belt attaching plate 18.

The plate 18, shown in perspective in Fig. 7, is cut out to provide a loop 19 adapted to receive one end 20 of the belt 15, as will be readily understood. Opposite the loop portion 19, the plate 18 has a gripper mounting flange 21 bent upwardly toward the cover plate 10 at an angle of slightly more than 90 degrees with respect to the body of the plate 18. The loop portion 19 of the plate 18 is also angularly bent with respect to the body of the plate a slight amount, as illustrated best in Figs. 4 and 5. The flange 21 has integral therewith a pair of 30 pivot pins 22 and 23 which are mounted in the bearings provided by the curved tongues 16 and 17 to pivotally mount the plate 18 upon the cover plate 10.

The flange 21 constitutes a mounting portion 35 for a gripping element 24 which is generally U-shaped in cross section with an elongated opening 25 in its base. The opening 25 receives the flange 21 which is undercut slightly at 26, and, after the gripping element 24 is seated on 40 the flange 21, this flange is pressed out to provide a pair of projections 27 and 28 that extend over the gripping element 24 and secure the element 24 to the flange 21. As shown best in Figs. 3, 5, and 6, the gripping element 24 may rock 45 upon the flange 21 and has a limited sliding movement on the flange 21 toward and away from the body of the plate 18. This is due to the clearance shown at 29 in Fig. 6.

The gripping element 24, as shown best in Figs. 50 6 and 8, has its side portions 30 and 31 diverging outwardly from the base. The side portion 31 is rounded at 32 to provide a central raised gripping portion for engaging the belt 15. The curvature of the edge 32 of the portion 31 is 55

greater than the curvature of the curved plate 10 so that the maximum gripping effect of this edge is at the center. The gripping element 24 has its end portions 33 and 34 bent to extend 5 toward the belt attaching plate 18 at an angle to the longitudinal axis of the gripping element 24. This angle is substantially so that the end portions 33 and 34 in the limited rocking movement provided for the element 24 may provide 10 gripping edges 35 and 36 that engage the belt to effect a better gripping of the belt and particularly of a thin belt. For example, as shown in Fig. 6, the dot and dash line 37 indicates the path of travel of the edge 32, while it is clear that 15 the edge 35 of the end portion 33 in turning about the same axis extends out beyond the line 37 and therefore will grip the belt tighter than the edge 32 in the extreme position shown in Fig. 5.

Fig. 1 shows the relation of the parts when the belt 15 is first inserted. The end gripping edges 35 and 36 are well back out of the way of the belt, and the only part that is in position to start gripping is the gripping edge 32. Now, 25 however, as the parts are advanced to the position shown in Fig. 4, the gripping edge 32 is caused to bite into the belt 15 and clamp it against the cover plate 10, the portion 30 of the gripping element 24 being moved away from the 30 flange 21 by the rocking movement of the gripping element 24 on the flange 21. Where the belt is so thin that the gripping edge 32 is insufficient to hold it, the plate 18 continues to turn with respect to the cover plate 10 until the 35 parts are in the position shown in Fig. 5. In this position, the angle which the flange 21 makes with the direction of pull upon the belt 15 is sufficient to cause the gripping element 24 to slide out, that is, away from the pins 22 and 40 23 and against the projections 27 and 28. Also, the angular position of the gripping element 24 with respect to the belt 15 is such that now the gripping edges 35 and 36 bite into the belt 15 as the gripping edge 32 passes its position of 45 maximum gripping to transfer the gripping action of the element 24 from the edge 32 to the edges 35 and 36.

It is believed to be evident from the foregoing description that I have provided a simple 50 economical and effective gripping mechanism for belt buckles of the character described. The cooperative features of the plate 18 and the gripping element 24 enable me to use buckles of the same specific structure and dimensions for belts 55 of a wide range of thickness.

Having thus described my invention, what I claim as new and desire to secure by Letters Patent is:

1. A buckle of the character described, comprising a cover plate, a gripper carrying plate pivoted to said cover plate and adapted to have a belt attached thereto, a gripping element, said gripping element having a slot therein, the gripper carrying plate having a part extending

through said slot, said slot being of greater width than the thickness of said part, and means on the gripper carrying plate cooperating with the gripping element to connect the gripping element to the gripper carrying plate for sliding and 5 rocking movement relatively thereto.

2. A buckle comprising a cover plate, a gripper carrying plate pivoted to said cover plate and adapted to have a belt attached thereto, said gripper carrying plate having a gripper mounting flange thereon extending toward the cover plate, said flange having spaced bearing surfaces facing the cover plate and a gripper holding portion located between and projecting beyond the bearing surfaces toward the cover plate, a gripping element having oppositely disposed leg portions, said gripping element being slotted intermediate its ends to receive said holding portion and having a connecting web portion at either end of said slot, said web portions riding upon said spaced bearing surfaces of the gripper carrying plate, and said holding portion having oppositely directed projections extending beyond the slot of the gripping element over said web portions to cooperate therewith and prevent the gripping element from sliding off the flange.

3. A buckle comprising a cover plate, a gripper carrying plate pivoted to said cover plate and adapted to have a belt attached thereto, said gripper carrying plate having a gripper mounting flange thereon extending toward the cover plate, said flange having spaced bearing surfaces facing the cover plate and a gripper holding portion located between and projecting beyond said bearing surfaces towards the cover plate, a gripping element having oppositely disposed leg portions, said gripping element being slotted intermediate its ends to receive said holding portion and having a connecting web portion at either end of said slot, the exterior surfaces of said web portions engaging said spaced bearing surfaces of the gripper carrying plate, and said holding portion having projections extending beyond the slot of the gripping element over the same to prevent the gripping element from sliding off the flange.

4. A buckle including a cover plate, a gripper carrying plate pivoted to said cover plate and adapted to have a belt attached thereto, a gripping element pivotally connected to the gripper carrying plate, said gripping element having oppositely disposed leg portions and a web portion connecting the same, one leg portion of said gripping element having end portions extending rearwardly from its intermediate portion and the pivotal axis of the gripping element at an acute angle to provide gripping edge portions correspondingly disposed at an acute angle to the gripping edge of its intermediate portion and projecting further than the same from the pivotal axis of the gripping element.

HERBERT BUCHSBAUM.
